UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

CARTRIDGE-LOADING CLIP.

1,161,688.

Specification of Letters Patent.

Patented Nov. 23, 1915.

Application filed November 2, 1914. Serial No. 869,920.

To all whom it may concern:

Be it known that I, THOMAS C. JOHNSON, a citizen of the United States, residing at New Haven, in the county of New Haven and State of Connecticut, have invented a new and useful Improvement in Cartridge-Loading Clips; and I do hereby declare the following, when taken in connection with the accompanying drawings and the characters of reference marked thereon, to be a full, clear, and exact description of the same, and which said drawings constitute part of this application, and represent, in—

Figure 1 a plan view on an enlarged scale 15 of a cartridge-loading clip constructed in accordance with my invention, with cartridges indicated by broken lines in engagement with the stop-fingers of the cartridge-retaining spring. Fig. 2 a view in side elevation of the loading-clip with the lower ends of the cartridges broken away. Fig. 3 20 a view of the clip in longitudinal central section on the line *a*—*b* of Fig. 1, with the lower ends of the cartridges similarly broken away. Fig. 4 a view of the clip in transverse section on the line *c*—*d* of Fig. 1. Fig. 5 a corresponding view on the line *e*—*f* of Fig. 1. Fig. 6 a corresponding view on the line *h*—*i* of Fig. 1. Fig. 7 a view showing 30 a cartridge engaged with the curved seat of one of the stop-fingers of the cartridge-retaining spring.

My invention relates to an improvement in cartridge-holding clips or packets of the 25 Mauser type, the object being to produce a convenient, effective and durable clip constructed with particular reference to avoidance of derangement in repeated use.

With these ends in view, my invention 40 consists in a cartridge-holding clip having certain details of construction and combinations of parts as will be hereinafter described and pointed out in the claims.

In carrying out my invention as herein 45 shown, I employ a one-piece sheet-metal clip-body slightly bowed from end to end, comprising a bottom 2 and two corresponding integral side flanges 3, 3, standing at a right angle to the said bottom 2 and extending 50 above and below the same as shown in Figs. 4 to 6 inclusive. The clip-body as thus made is I-shaped in cross-sectional form, producing in the outer face of the body a shallow channel 4 for the reception of a 55 sheet-metal cartridge-retaining spring 5.

provided at its projecting ends with stop-fingers 6 bent at a right angle to the axis of the said spring and positioned to normally block the ends of the cartridge-head recess or channel 7 formed upon the inner 60 face of the clip-body, extending throughout the length thereof, and complementing the spring-receiving channel 4. The inner edges of the side-flanges 3 of the clip-body are turned inward at a right angle to form 65 bearing-flanges 8 extending toward each other and engaged by the circular flanges 9 produced by forming cannelures 10 in the butt-ends or heads of the cartridges 11, which are thus held in place. 70

The cartridge-retaining spring 5 is held in place in the bottom of the channel 4 by means of two oppositely located fingers 12 cut from the inside walls of the folded outer edges of the side flanges 3 midway the 75 length thereof and turned down upon the edges of the spring midway the length of the same, as shown in Figs. 1 and 5.

To permit the cartridges 11 to be fed out of the clip into the gun, the cartridge-retaining spring 5 is provided with two pairs of laterally extending operating-arms 13 which project through cuts 14 formed in the respective side flanges 3, and have their projecting outer ends turned inward for 80 their better co-action with the inclined surfaces formed, as usual, in the gun for springing the ends of the said spring 5 so as to clear its stop-fingers 6 from the circular flanges 9 of the cartridges. As shown, 85 the spring 5 is stiffened by three parallel ribs 15 extending nearly throughout its length. The lateral operating-arms 13 are also stiffened by ribs 16 extending outward from the outer ribs 15. 90

To prevent the ends of the spring 5 from being sprung beyond their limit of complete recovery, it is furnished near each of its ends with a pair of laterally arranged safety-fingers 17 extending under stop-lugs 18 cut from the inner faces of the outer edges of the side flanges 3 and turned over the said fingers 17 as shown in Fig. 3, whereby the play of the ends of the spring 5 is held within safe limits. 95

The cartridge-stop fingers 6 formed upon the projecting ends of the spring 5 and playing in clearance cuts 19 in the ends of the bottom 2 of the clip-body, have their extreme ends shaped to form curved seats 110

20 conforming in curvature to the curvature of the circular flanges 9 of the cartridges, whereby the end cartridges are more securely held and less liable to be accidentally 5 displaced or ridden over the stop-fingers 6.

I claim:—

1. In a cartridge-holding clip, the combination with a channeled clip-body, of a cartridge-retaining spring applied to the outer 10 face of the said body and adapted to retain the cartridges therein and to be operated for their successive release, and provided at each end with one or more laterally arranged safety-fingers co-acting with the said clip-body on the outside thereof for preventing the ends of the said spring from being over-sprung for releasing the cartridges.

2. In a cartridge-holding clip, the combination with a channeled clip-body, of a cartridge-retaining spring applied to the said 15 20

body and furnished at its ends with cartridge-stop fingers shaped to form curved seats for the heads of the cartridges.

3. In a cartridge-loading clip, the combination with a channeled clip-body, of a cartridge-retaining spring applied to the said body and formed with laterally projecting operating-arms, the said spring being furnished with three parallel stiffening ribs and the said operating-arms being stiffened by ribs merging into the said longitudinal stiffening ribs.

In testimony whereof, I have signed this specification in the presence of two subscribing witnesses.

THOMAS C. JOHNSON.
